UNITED STATES PATENT OFFICE

2,252,402

FILING EQUIPMENT

Emil Kern, Long Island City, N. Y., assignor to
 Acco Products, Inc., Long Island City, N. Y., a
 corporation of New York

Original application December 31, 1938, Serial No.
 248,693. Divided and this application October
 18, 1939; Serial No. 299,950

6 Claims. (Cl. 45—2)

This application is a division of my co-pending application Serial No. 248,693, filed December 31, 1938.

The invention relates to improvements in filing equipment and more particularly to filing units and means for mounting said units in a cabinet or the like.

Large drawings, maps, samples and the like are not easily filed and maintained accessible in some types of filing equipment because often such drawings, maps and etc., must be filed horizontally in a stack. Other known types of filing equipment such as those disclosed in Patents 1,867,158 and 1,867,159, consist of a filing cabinet or open rack provided with removable filing units from which the drawings, maps or the like are suspended. The present invention embodies improvements in the latter type of filing equipment.

It is therefore, an object of the invention to provide filing equipment with simple, efficient and inexpensive filing units to facilitate suspension or vertical filing.

Another object is to provide a vertical filing unit with hanger arms constructed and arranged to readily receive slidable suspension members.

Another object is to provide inexpensive slideable sheet suspension members embodying means to retain them in place on hanger arms.

The foregoing and such other objects of the invention as will appear hereinafter, will be more readily understood from a perusal of the following specification, in which reference will be made to the accompanying drawing, wherein:

Fig. 1 is a fragmentary vertical sectional view of a cabinet having one embodiment of the improved filing unit mounted therein.

Fig. 2 is a fragmentary horizontal sectional view of the cabinet shown in Fig. 1.

Fig. 3 is a vertical sectional view similar to Fig. 1, showing another form of filing unit.

Fig. 4 is a vertical sectional view similar to Fig. 3, showing another modification.

Fig. 5 is a fragmentary sectional view, taken on line 5—5 of Fig. 4.

Fig. 6 is a transverse sectional view, taken substantially on line 6—6 of Fig. 4.

Fig. 7 is a vertical sectional view, similar to Fig. 4, showing another form of suspension unit.

Fig. 8 is a fragmentary sectional view showing a modified form of a tubular hanger arm mounting.

Fig. 9 is a fragmentary view, similar to Fig. 8, showing another form of hanger arm and mounting.

Throughout the description like numerals identify corresponding parts in the drawing.

The improved filing units are shown mounted within a cabinet 11. Suitable filing unit supports 12 and 13 extend transversely of said cabinet and preferably are secured at their ends at a fixed height, but, if desired, they may be mounted in said cabinet for vertical adjustment. The horizontal supports 12 and 13 afford a mounting for the novelly constructed filing units, each of which comprises a hanger arm 14 and a suspension member 15, slidable thereon, to which the file contents, such as sheets 16, are secured.

In the embodiment shown in Figs. 1 and 2 inclusive, the arm 14 is turned down as at 17 and extends through an elongated hole 18 in the horizontal flange of the rear support 12, thereby providing a loosely fitted pivotal mounting enabling the arm to tilt downwardly sufficiently to dispose its free forward end below the bottom edge of the front support 13. The degree of tilting is limited in this instance by the vertical wall of the rear support 12, as illustrated in broken lines in Fig. 1. While the arm 14 is in its tilted or forwardly inclined position, the suspension member 15 can be freely slid onto or withdrawn from the end of the arm.

Each suspension member 15 preferably is formed from a stiff sheet such as metal, heavy cardboard, fabric composition or the like, folded longitudinally to a substantially U-shape to provide spaced apart side walls, preferably of uniform depth. Said walls preferably are apertured to readily receive the prongs of suitable fasteners 19 provided to securely clamp or bind sheets 16 between said walls. Obviously, other types of detachable fasteners may be used but if the files are made for permanent filing, rivets, staples or other fastening means may be employed.

It should be noted that the upper edges of sheets 16 are spaced below the rolled edge of the U-shaped member 15 so that a space is maintained along said edge to freely admit the hanger arm 14.

After a suspension member 15 has been slipped over the downwardly tilted arm 14, an upstanding hook 21 (Fig. 1) carried on the forward end of the slidable member 15, is engaged over the edge of a hole 22 in the front support 13 to hold the assembled filing unit horizontally. A like hook may be provided at each end of the suspension member to make said member reversible. While the hook is in engagement with the front support, the filing unit cannot be swung

about its pivot. To remove the suspension member, the hook 21 is disengaged from the front support and the arm is permitted to tilt downwardly, whereby the member 15 can be freely slid off.

Filing of the various suspension members is facilitated by the suitable tab receptacles 23 provided on each member and on the front support, as at 24, to receive index tabs. Instant return of a suspension member onto its hanger arm is facilitated by the downward tilting of said arm which aids its being located and positions it to readily receive the member. Accordingly, any suspension member withdrawn is readily returned to its proper place in the filing cabinet.

The structure illustrated in Fig. 3 is similar to that shown in Fig. 1. Here the front support 13a has a hook 22a engaged by a ring or eyelet 21a carried in the forward end of the suspension member 15a. The ring or eyelet 21a serves as a handle to facilitate sliding of the member 15a. The member can be made reversible by providing a ring or eyelet at each of its ends.

In the device shown in Figs. 4 to 6 inclusive, a rigid mounting is provided for the removable hanger arms 14b. In this embodiment, the hanger arms are tubular and each has a vertical reinforcing rib 25 formed thereon, which terminates at its rear end in oppositely disposed flanges 26. The rear support 12b preferably is substantially U-shaped in cross section and is formed with one wall slotted at intervals to receive the rear ends of the ribs 25. As shown, the flanges 26 are snugly embraced in the U-shaped support to retain the hanger arms substantially horizontally. Obviously, the support 12b could be formed of two closely spaced apart bars. As best illustrated in Fig. 6, the tubular arm 14b is slotted longitudinally along its bottom to telescopically receive the rolled edge 27 of a singled walled suspension member 15b.

The bottom wall of the tubular hanger arm 14c shown in Fig. 7 also is slotted to receive a suspension member 15c and its rear portion 17c is turned downwardly to provide a rigid pivotal mounting in the rear support 12. The free forward end of the hanger arm is supported by a cable 28 secured, at one end, preferably to the rear wall of the cabinet 11.

In the device illustrated in Fig. 8, the tubular hanger arm 14d also is formed with a slot and is apertured at 29, adjacent its rear end, to receive a supporting lug 31 preferably struck out from the rear support 12d.

The hanger arm 14e shown in Fig. 9 has an offset hook-like end portion 32 which fits over the upper one of two rear supports 12e. The lower end of the hook-like portion 32 co-acts with the lower support to retain the arm substantially horizontally.

The filing equipment described provides a simple, inexpensive, compact and convenient filing system. It may be employed for storage of any number of sheets or the like. The filing units may include any of the various suspension members illustrated, associated with any of the various types of hanger arms and supporting means applicable to such use.

I claim:

1. In a filing device, a filing unit comprising, in combination, a support, an arm mounted for pivotal movement on said support, a suspension member slidably supported on said arm having means adapted to secure sheets or the like thereto, a second support, and means on one end of the member to engage said second support.

2. In a filing device, in combination, a support, an arm movably mounted at one end to said support arranged to tilt downwardly, means to limit the tilting, a sheet suspension member telescoped on said arm, a second support, and means on said second support to co-act with means on said member to retain the arm substantially horizontally.

3. In a filing device, in combination, a support, an arm movably mounted at one end to said support arranged to tilt downwardly, means to limit the tilting, said arm being mounted for pivotal movement through a substantially horizontal plane, a sheet suspension member telescoped on said arm, a second support, and means on said second support to co-act with means on said member to retain the arm substantially horizontally and prevent pivotal movement thereof.

4. In a filing device, in combination, a support, an arm loosely mounted at one end on said support for tilting downwardly, means to limit the tilting, a sheet suspension member telescopically mounted on said arm, a second support, and means on said member to co-act with said second support to retain the arm and member substantially horizontally.

5. In a filing device, in combination, a support, an arm mounted at one end to said support for tilting downwardly, means to limit the tilting, a sheet suspension member telescopically mounted on said arm, a second support, and means on said suspension member to co-act with said second support to prevent displacement of said member.

6. In a filing device, in combination, a support, an arm mounted at one end to said support for pivotal movement through a substantially horizontal plane and downward tilting, means to limit the tilting, a sheet suspension member telescopically mounted on said arm, said member being slidably over the free end of said arm, a second support, and means on said suspension member to co-act with said second support to prevent pivotal movement and maintain said member and arm substantially horizontally.

EMIL KERN.
